UNITED STATES PATENT OFFICE

2,365,143

MULTIPLE CONTAINER

William M. Emery, Shaker Heights, Ohio

Application February 16, 1944, Serial No. 522,548

12 Claims. (Cl. 132—82)

My invention refers to multiple containers and more especially to those adapted to conveniently hold face powders and also facial creams, greases, pastes and other peculiar forms of cosmetics. They may be called compacts and are most commonly carried in ladies' hand bags.

Objects of my invention are to provide:

A convenient and compact container for carrying face powder, powder puff and mirror and also small quantities of a variety of facial cosmetics, such as rouge, eye shadow, cold cream, etc.

A unit container to carry a plurality of different cosmetic pastes and the like so that each is individually and securely closed.

A plurality of containers some of which are substantially similar in shape and size suitable for carrying different cosmetics and having means to easily differentiate between the containers.

A relatively larger container and a plurality of relatively smaller containers attached to protrude from the bottom of the large container, none of the containers communicating with the other.

Further objects and novel features of my invention will be apparent from the following specifications and claims when considered together with the accompanying drawing in which:

Fig. 1 is a top plan view of an embodiment of my invention.

Fig. 2 is a side elevation of the same embodiment.

Fig. 3 is a bottom plan view of the same embodiment.

Fig. 4 is a sectional view of a small container.

Fig. 5 is a sectional view of another embodiment having many similar characteristics and viewed from line 5—5 of Fig. 6.

Fig. 6 is a bottom plan view of the embodiment of Fig. 5.

Fig. 1 shows a tight fitting lid 10, attached by hinge 11 to body 12 which includes a bottom portion 13 and a four-sided wall portion 14 with radius corners 15 integral with the bottom section 13 and forming an annular section. These parts define a hollow interior substantially similar to that shown in Fig. 5 indicated by 55 hereafter described, which is suitable for carrying a mirror, powder puff and face powder in loose or cake form.

Four blind and threaded sockets 16 in the bottom portion 13 similar to those shown in Fig. 5 and identified as 56 and also 46, are grouped around the center of the bottom portion 13 substantially equally spaced relative to each other. Four cups 17 similar to the embodiment shown in Fig. 4 are screwed into the sockets 16. The radius of these cups are substantially similar to the radius of the corners 15 and the centers of

these radii are respectively in substantial alignment.

The cups are designed to hold cosmetic greases and pastes and the like and are each individually sealed by its threaded connection with the bottom portion 13 which is imperforate so that one will not run into the other nor leak if the container should become over-heated nor will the greases become contaminated by the powder.

Each cup although generally similar in shape and symmetrically and geometrically arranged is designed to contain different cosmetics. In order for the user to quickly differentiate between them and accordingly to select the one containing the desired cosmetic, I provide visual means for identifying them such as making the cups of different colors, such as red, white, blue and cream.

One method of construction would be to make many of the parts of plastic material which provides distinctive and brilliant colors.

Fig. 4 shows a small cup such as 17 which includes a male threaded portion 18 and a hollow portion 19. The thread may be cast in the plastic but in many cases would be machined. The thread may be tapered in which event the shoulder 20 may be omitted. The bottom of the cup may be slightly convex as shown or may be flat.

Fig. 5 shows a round lid 50 threaded at 51 to a round body 52 which is composed of a bottom portion 23 with annular walls 54. The body 52 has the general shape of a thin cylinder and defines a hollow portion 55 suitable for containing face powder, loose or in cake form, a powder puff and a mirror.

Three blind and threaded sockets 56 in the bottom 53 are grouped around the center of the bottom 53 and substantially equally spaced 40 relative to each other. Three cups 57 such as 17 shown in Fig. 4 are screwed into the socket 56. These cups may be many sided as shown in Fig. 6. In all events, the perimeter of the cups at one point lines up substantially with the circumference of body 52 providing cups of the greatest diameter that it is practical to have within the limits of body 52 or 12.

While color seems to be the best method of differentiating the cups since this does not involve die changes, without departing from the spirit of my invention any distinctive marking or shaping may be used.

Also the hinged lid 10 shown in Figs. 1 and 2 could be used in place of the threaded lid 40 shown in Fig. 5 and vice versa. Also the cups 57 may be substituted for cups 17 or vice versa. Also the number of the cups used in either design may be varied such as using four cups in Figs. 5 and 6.

For these reasons I do not limit the field of my

invention to the embodiments or applications shown or described herein as many modifications are possible without departing materially from the spirit of my invention as I have demonstrated.

Accordingly I claim:

1. In a multiple container, the combination of a top box having a circular bottom portion, three smaller and substantially cylindrical boxes arranged equally spaced each from the other with part of the periphery of each smaller box lining up with the circumference of the circular bottom portion and screw thread means on each smaller box to attach it to the bottom portion of the top box.

2. In a multiple container, the combination of a box having a bottom, a four-sided wall section integral therewith having a radius corner where the sides join each other and a tightly fitting top therefor, cooperating means between the wall section and the top to facilitate the opening and closing of said box, four substantially cylindrical smaller boxes, means for distinguishing between the four smaller boxes to facilitate the use of each for different contents, individual screw threaded connections between each of the smaller boxes and the bottom of the first mentioned box for individually closing and attaching each box, the cylindrical radius of the smaller boxes being substantially similar to the radius of the said corner and positioned adjacent thereto.

3. In a multiple container, the combination of a box having a bottom, a four-sided wall section and a tightly fitting top therefor, cooperating means between the wall section and the top to facilitate the opening and closing and sealing of said box, four smaller boxes to hold contents each different from the other, individual screw threaded connections between each of the smaller boxes and the bottom of the first box for closing and attaching each thereto, and color means to differentiate between the smaller boxes to facilitate the selection of the box containing the desired contents.

4. In a multiple container, a round flat box, a screw threaded top therefor, three smaller round boxes to hold contents each different from the other and symmetrically grouped around the center of the bottom of the first mentioned box and protruding therefrom, individual threaded connections between each of the smaller boxes and the bottom of the first box and color means to differentiate between at least the smaller boxes to facilitate the easy selection of the box having the desired contents.

5. In a small compact container, the combination of top box having a bottom portion, an annular wall portion and a tightly fitting cover section, cooperating means between the annular wall portion and the cover section to effect easy opening and closing of the top box, said top box being suitable for holding face powders and the like, a plurality of smaller boxes symmetrically attached around the center of the bottom portion of the top box and extending downwardly therefrom, said smaller boxes being suitable for retaining various and different cosmetics of a pasty or greasy consistency, an easily separated connection between each of the smaller boxes and the bottom of the top box to individually close and attach each smaller box, and visual means to distinguish each box one from the other to differentiate between contents.

6. In a container the combination of a top box having a bottom, an annular wall and tight fitting cover means and means associated with the cover to allow easy opening and closing of said box, and a plurality of smaller bottom boxes geometrically grouped closely about the center axis of the top box, individual threaded means to attach each of the smaller bottom boxes individually to the bottom of the top box thereby closing each bottom box individually and visual means to differentiate each of the bottom boxes one from the other.

7. In a container, the combination of a compact box having tightly fitting lid, means to open and close the lid and a plurality of smaller boxes grouped closely about the center of the bottom of the first box and individual thread means to attach each of the smaller boxes to the bottom of the first box and to tightly close each box individually.

8. In a container, the combination of an imperforate bottom section, a hollow wall section integral therewith, a lid screw threaded thereto, said parts defining a relatively flat cavity suitable for keeping face powders and the like, a plurality of small cups arranged each adjacent to the other and suitable for containing cosmetic pastes and the like and threaded means to mount each of said cups on the bottom section so that they depend downwardly therefrom.

9. In a multiple container, the combination of a box having a bottom, a four-sided wall section and a tightly fitting top therefor, cooperating means between the wall section and the top to facilitate the opening and closing and sealing of said box, four smaller boxes and individual screw threaded connections between each of the smaller boxes and the bottom of the first box for closing and attaching each thereto.

10. In a multiple container, a round flat box, a screw threaded top therefor, three smaller round boxes symmetrically grouped around the center of the bottom of the first mentioned box and protruding therefrom and individual threaded connections between each of the smaller boxes and the bottom of the first box.

11. In a small compact container, the combination of a top box having a bottom portion, an annular wall portion and a tightly fitting cover section, cooperating means between the annular wall portion and the cover section to effect easy opening and closing of the top box, said top box being suitable for holding face powders and the like, a plurality of smaller boxes symmetrically attached around the center of the bottom portion of the top box and extending downwardly therefrom, said smaller boxes being suitable for retaining various and different cosmetics of a pasty or greasy consistency, and an easily separated connection between each of the smaller boxes and the bottom of the top box to individually close and attach each smaller box.

12. In a container, the combination of a top box having a bottom, an annular wall and a tight fitting cover means, and means associated with the cover to allow easy opening and closing of said box, and a plurality of smaller bottom boxes geometrically grouped closely about the center axis of the top box, and individual threaded means to attach each of the smaller bottom boxes individually to the bottom of the top box thereby closing each bottom box individually.
